UNITED STATES PATENT OFFICE.

JOSEPH HAINES, JR., OF MEADOWBROOK, AND HAROLD F. PAGET, OF PHILADELPHIA, PENNSYLVANIA, ASSIGNORS TO HAINES HOSIERY MILLS, INC., OF PHILADELPHIA, PENNSYLVANIA, A CORPORATION OF PENNSYLVANIA.

DESIGN FOR A STOCKING.

Application filed January 26, 1928. Serial No. 25,047. Term of patent 3½ years.

To all whom it may concern:

Be it known that we, JOSEPH HAINES, Jr., and HAROLD F. PAGET, citizens of the United States, the former residing at Meadowbrook, in the county of Montgomery and State of Pennsylvania, and the latter residing at Philadelphia, in the county of Philadelphia, and State of Pennsylvania, have invented a new, original, and ornamental Design for Stockings, of which the following is a specification, reference being had to the accompanying drawing, forming part thereof.

Figure 1 is a front elevation of one side, and Figure 2 is a front elevation of the other side of the stocking, showing our new design.

We claim:

The ornamental design for a stocking, as shown.

JOSEPH HAINES, JR.
HAROLD F. PAGET.
